ROBERT GRANT, OF CHICAGO, AND FRED C. MAIRSON, OF FOREST PARK, ILLINOIS.

PRINTING-MACHINE.

1,235,135.

Specification of Letters Patent. Patented July 31, 1917.

Application filed March 8, 1916. Serial No. 82,821.

To all whom it may concern:

Be it known that we, ROBERT GRANT and FRED CHARLES MAIRSON, citizens of the United States, residing, respectively, at Chicago and Forest Park, in the county of Cook and State of Illinois, have invented certain new and useful Improvements in Printing-Machines, of which the following is a specification.

10 Our invention relates to improvements in printing machines, and more particularly to that type of a printing machine commonly known as the Gordon press, in which the ink rollers pass over a revoluble inking disk and 15 over the face of the type secured in the swinging type and disk carrying arm.

The objects of our improvements are to provide means for the purpose of adjusting the inking rollers so that no matter what the 20 diameter of said rollers may be (within certain reasonable limits) the pressure upon the face of the type and upon the inking disk may be maintained at always a uniform pressure until the rollers have become worn so 25 that they are practically useless; and, to provide an attachment, for the above stated purpose, to said style of press, without changing the construction in any way, shape or manner, except to provide some tapped 30 holes, and, a pair of drilled holes for the adjusting eccentric stud; and, to provide adjustable inking-roller-carrying-rails for the purpose as above stated.

These and other objects of our improvements will be more clearly pointed out in the accompanying drawings, specification and appended claims.

In the accompanying drawings:—

Figure 1, represents a side elevation of 40 part of a press, of the above stated kind, showing our invention embodying our improvements attached, and, partly broken away, showing the other side, or far rail, and, also showing the type and type frame 45 in section.

Fig. 2, represents a side view (on a larger scale) of one of the adjustable inking roller-carrying rails, detached from the type carrying arm of the press. 50 Fig. 3, is a section on line A—A of Fig. 2, showing the adjusting eccentric stud, and, showing in section, part of one side of the type carrying arm.

Fig. 4, is a section on either of lines B—B,

also of Fig. 2, showing the clamping screw 55 for the said rails, and showing in section, part of one side of the type carrying arm.

Fig. 5, is a side view which represents that part of one side of the present type-carrying-arm, of which the one edge is parallel with the type and with the rotating inking disk. In the drawing is also shown the tapped holes and one of the drilled holes previously mentioned.

Fig. 6, is a side view of our improvements 65 as attached to the type carrying arm, but on a larger scale and showing it moved back so that the roller carrying face, edge, or track, coincides with, or being in the same plane as, those of the type carrying arm, 70 thereby making up for the reduced diameter of the inking rollers, caused by wear.

Fig. 7, is a detailed view of the eccentric adjustment stud.

Similar characters refer to similar parts 75 throughout the several views.

In Fig. 1, will be seen our invention as attached to the type and inking-disk-carrying arm (2), of a printing press (A), commonly known as the Gordon press. In the same 80 figure will be seen the inking roller-carrying arm (B) broken away in order to more clearly show the main points relative to the invention, and to the inking rollers (3), and the traveling rollers (4), which are mounted 85 on shafts (5), revolvably mounted in bearings (D), which are not shown on the near side, but which are secured to the partly shown tension members, or rods (C), which are carried in the arm (B). The plates (A¹) being the invention embodying our improvements are so constructed that the edges (A²) will be parallel with the edges (A³), of the arm (2), except at the curved portions (A⁴) and (A⁵). 90

It will also be noticed, in Fig. 1, that the type face (A⁶), and the inking disk (A⁷), are shown slightly away from the surfaces (A⁸) of the arm (2), but are, respectively, parallel with the edges (A²) and (A³). 100 And in views Fig. 1, Fig. 2, and Fig. 6, counter slotted holes (A⁸) and (A⁹) are shown, arranged in the direction of the arrows, which is in an angular direction midway of the plane of the type face (A⁶) and the inclined face or plane of the disk (A⁷); 105 and through these slotted holes are inserted flat head screws (6), which are tapped into

the arm (2) at (7), as shown in Fig. 5, more clearly.

In the plate (A¹), shown more clearly in Fig. 2, and substantially midway between the counter slotted holes (A⁸) and (A⁹), is a slotted hole (A¹⁰) at right angles to the slotted holes (A⁸) and (A⁹), and, at right angles to said slotted hole (A¹⁰) is an elongated counter-bore (A¹¹) shown on the reverse side of the plate (A¹) in dotted lines. Through this slotted hole (A¹⁰) and in the counter bore (A¹¹) is inserted an eccentric adjusting stud (8), and in arm (2) is a drilled hole (9) to receive the end (10) of the stud (8). It is obvious therefore, that any slight turn of said stud (8), in either direction, will move the plate (A¹). But in order to move said plates, the clamping screws, or plate locking screws (6) have to be loosened, and when said plate is adjusted, by means of said stud, to its proper place, said screws (6) are tightened and lock said plates (A¹) to their place. Now, as the edges (A²) of the plates (A¹) are adjustably parallel to or from the face of the type (A⁶) and the face of the inking disk (A⁷), it can be clearly seen that any variation of the diameters of the inking rollers (3), can be readily compensated for by the inward or outward adjustment of the adjustable plates, or rails (A¹). Therefore:—

Having thus described our invention, the merits of our improvements can be readily understood, and it will be seen that the minor details of our construction can be altered in many ways without departing from the spirit of our invention, but what we

claim and desire to secure by Letters Patent is—

1. The combination in inking-roller carrying-rails, in combination with a printing machine of the class set forth, of, detachably secured side plates, or rails, adjustably mounted on the outer sides of the type and inking-disk carrying-arm, with their inking roller carrying edge, or track parallelly adjustable to, or from, the face of the type and the surface of the inking disk; of means for adjusting said tracks consisting of eccentric track adjusting studs engaging said tracks and revolvably held in the type and disk carrying arm by said side plates, and track clamping, or locking screws tapped into said carrying arm.

2. The combination in a means for compensating for the decreased or increased diameters of inking rollers, in a printing machine of the class set forth, of, adjustably secured side plates, or tracks, mounted on the type and inking-disk-carrying-arm, with its roller carrying edge or track parallelly adjustable to or from the face of the type and the surface of the inking disk; adjustable track engaging eccentric studs mounted in the type carrying arm and held in place by said plates; clamping, or side plate locking screws tapped into the type carrying arm.

ROBERT GRANT.
FRED C. MAIRSON.
